(57) **CLAIM**

The ornamental design for a cabinet, as shown and described.

DESCRIPTION

FIG. 1 is a front, bottom, left perspective view of a cabinet, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, bottom, right perspective view thereof, with the doors in an open position.

The broken lines in the drawings illustrate the portions of the cabinet, which form no part of the claimed design.

1 Claim, 8 Drawing Sheets
